MEASURING CUP

Wendell W. Jennings, San Francisco, Calif.

Application December 16, 1946, Serial No. 716,541

5 Claims. (Cl. 73—429)

1

This invention relates to, and it is an object to provide, an improved measuring cup for culinary use; the cup being designed for effective use with dry ingredients, semi-solids or oils, and liquids.

Another object of the invention is to provide a measuring cup which is fitted with a movable bottom whereby to selectively vary the capacity of the cup relative to an included scale; the cup having a handle, and there being a lever mechanism operative from the handle to cause such movement of the bottom to a selected position.

A further object of the invention is to provide a measuring cup adapted to receive an initially separate, disposable insert cup therein for the purpose of measuring certain ingredients, such as oils, semi-solids, etc.; both cups being transparent to facilitate the measuring operation.

A further object of the invention is to provide a simple, accurate, practical, and easy-to-use measuring cup, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the improved measuring cup, with the bottom in lowered position.

Fig. 2 is a sectional elevation of the measuring cup in a raised position to reduce the capacity of the cup to a selected extent.

Fig. 3 is a top plan view of the measuring cup.

Referring now more particularly to the characters of reference on the drawings, the numeral 1 indicates a cylindrical cup, preferably of a transparent plastic, and fitted with a vertically movable bottom 2 of similar material; such bottom 2 including a dependent annular skirt 3 which guides said bottom for vertical sliding motion, with a close fit, in the cup 1, whereby to selectively vary the capacity of the latter.

At its lower end the cylindrical cup 1 includes an annular stop 4 which prevents escape of the bottom 2 from said cup.

On one side the cup 1 is fitted with a rigid, laterally outwardly projecting handle 5 which is flat in a vertical plane, and which handle extends substantially from top to bottom of the cup. The handle 5 includes a finger opening 6.

An actuating lever, a bellcrank type, indicated generally at 7, is disposed with one leg 8 upstanding alongside the handle 5, and with the

2

other leg 9 projecting inwardly through a slot 10 in the adjacent side of the cup 1 below the bottom 2. The bellcrank actuating lever 7 is pivoted, intermediate its ends, as at 11, to the handle 5 adjacent the slot 10.

Below the bottom 2 the leg 9 is formed with an offset, as at 12, so that the inner end portion of said leg may extend diametrically of the cup through an opposed fulcrum opening 13 formed in the lower end of a depending lug 14 fixed centrally on the bottom 2. It will be seen that upon swinging of the bellcrank actuating lever 7, the leg 9 will cause vertical motion of the bottom 2 in the cup 1.

At the upper end of the leg 9 it is fitted with a thumb pad 15, and a laterally extending finger 16, which rides—frictionally—on the upper edge 17 of the handle 5; such edge being arcuate and concentric to the pivot 11. Along said arcuate

upper edge 17 it is notched at spaced points, as at 18, and adjacent each notch 18 there is an indicia 19 representing dry measurements. For making dry measurements the user of the described measuring cup places the index finger through the opening 6 and the thumb on the pad 15, shifting the actuating lever 7 until the finger 16 drops into the notch 18 corresponding to the desired measurement as evidenced by the indicia 19. When this is done the bottom 2 is shifted, vertically, to a corresponding position in the cup 1. Thereafter when the cup is filled, above the adjusted bottom, it will hold an amount corresponding to the set position of the lever 7. For measuring semi-solids, oils, or the like, which might tend to gum the movable bottom 2, the latter is placed in its lowermost position, and the cup is used as follows:

An initially separate disposable cup 20, of wax paper or the like, is inserted in the cup 1 until the bottom of said cup 20 rests on the bottom 2. The disposable cup 20 is transparent, as is the cup 1, so that the ingredient to be measured may be placed in said disposable cup and read on a measuring scale 21 on the outside of cup 1.

The initially separate, disposable cup 20 is formed of a size so that it projects upwardly somewhat, as at 22, to compensate for its displacement in the cup 1. Further, the sides of the cup 1 taper from top to bottom, as at 23; the advantage being ease of initial manufacture, nesting for transport, and wedging of said cup 20 in the cup 1 in use so that ingredients may be poured from the device without displacement of said cup 20.

Under certain conditions, as for use with liquids

such as milk, water, etc., the device may be used as a conventional, fixed measuring cup, by lowering the bottom 2 to its lowermost position and reading the contents on a scale 24 on the cup 1 alongside the scale 21.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention as set forth herein.

Having thus described the invention, the following is claimed as new and useful and upon which Letters Patent are desired:

1. A measuring cup comprising a cup having a laterally projecting handle, a vertically movable bottom slidably mounted in the cup, the cup being provided with an opening in its side below the movable bottom, a bellcrank lever pivoted intermediate its ends on the handle for swinging in a vertical plane transversely of the cup, one leg of the lever upstanding alongside the handle, the other leg of the lever projecting inwardly through said opening and being connected to the bottom, and a finger pad on said one leg accessible from the handle.

2. A measuring cup comprising a cup having a laterally projecting handle, a vertically movable bottom slidably mounted in the cup, the cup being provided with an opening in its side below the movable bottom, a bellcrank lever pivoted intermediate its ends on the handle for swinging in a vertical plane transversely of the cup, one leg of the lever upstanding alongside the handle, the other leg of the lever projecting inwardly through said opening and being connected to the bottom, and a finger pad on said one leg accessible from the handle; said one leg having a projecting element slidably but frictionally bearing against the handle, there being spaced element receiving notches on the handle along the

path of said element, and measurement indicia adjacent said notches.

3. A measuring cup comprising a cup having a laterally projecting handle, a vertically movable bottom slidably mounted in the cup, the cup being provided with an opening in its side below the movable bottom, a bellcrank lever pivoted intermediate its ends on the handle for swinging in a vertical plane transversely of the cup, one leg of the lever upstanding alongside the handle, the other leg of the lever projecting inwardly through said opening and being connected to the bottom, and a finger pad on said one leg accessible from the handle; the handle having an arcuate upper edge concentric to the lever pivot, a laterally projecting finger on said one leg slidably but frictionally bearing on said edge, there being spaced finger receiving notches in said arcuate upper edge of the handle, and measurement indicia adjacent said notches.

4. A measuring cup as in claim 3 in which the handle has a finger opening therethrough; the finger pad being on said one leg above such finger opening.

5. A measuring cup comprising a transparent cup with measuring indicia on its side, a bottom slidably movable through said cup, the cup being provided with an opening in its side below the bottom, a bellcrank lever pivoted adjacent the outside of the cup, one leg of the lever extending through said opening and being connected to the bottom, and the other leg of the lever extending along the outside of the cup.
